H. CASLER

SKATE WHEEL

Filed Feb. 11, 1924

Inventor.

A 22 Herman Casler

By Percy H. Moore

Atty.

UNITED STATES PATENT OFFICE.

HERMAN CASLER, OF CANASTOTA, NEW YORK, ASSIGNOR TO PRODUCTION ENGINEERING CORPORATION, OF CANASTOTA, NEW YORK.

SKATE WHEEL.

Application filed February 11, 1924. Serial No. 692,111.

To all whom it may concern:

Be it known that HERMAN CASLER, a citizen of the United States, residing at Canastota, in the county of Madison and State of New York, has invented certain new and useful Improvements in Skate Wheels, of which the following is a specification.

My invention relates to skate wheels and has for its object to provide a strong, efficient wheel of economical construction, the parts of which can be easily and quickly assembled.

Other and further objects and advantages will be in part described and in part obvious as the description is proceeded with.

In the accompanying drawings forming part of this specification—

Figure 1 is a view in elevation of a roller skate wheel embodying my invention;

Figure 2 is a view in transverse section of the same on the line 2—2 of Figure 1; and

Figure 3 is a section on the line 3—3 of Figure 2.

Referring more particularly to the drawings wherein like reference numerals refer to corresponding parts throughout the several views, 5 denotes a roller skate wheel comprising an axle 6, mounted in hub 7. 30 Inner and outer washers 8 and 9 bear against the respective ends of the hub 7, and are held in place upon the axle by inner and outer dust caps 10 and 11, the inner cap 11, being welded or otherwise suitably secured to the usual skate bracket 12.

Ball bearings 13 which rest upon the hub 7, are confined between the plates 8 and 9 by inner and outer bearing cups 14 and 15, it being understood that the cups are rotatably supported upon the hub 7, by means of the bearings. Wire coils 16 and 17 seated in grooves 18 and 19 in the ends of the hub prevent displacement of the balls should the plates 8 and 9 be removed for inspection or repairs. It will be noted that the bearing cups 14 and 15 have central openings 30 and 31, also peripheral side flanges 32 and 33 respectively.

A peripheral wheel cup or tread member

20 is supported at its outer side upon the cup 15, by the side wall 21 of the tread member 20, and at its other side is supported upon a disc 22, which in turn snugly seats upon the bearing cup 14, a flange 34 on the member 20 being provided for a purpose about to be described.

Positioned between the side wall 21 and the disc 22, are inner and outer ring like bands 23 and 24, the former being of a size to span and seat snugly upon the bearing 60 cups, and the latter being of a size to seat snugly against the inner periphery of the tread member 20 and against the inner face of the disc 22. These bands 23 and 24 tightly clamp the disc 22 against the aforesaid flanges 32 and 34. The side wall 21 of the tread member is preferably provided with apertures 25, to facilitate assembly of the various parts. It will be noted that the bands 23 and 24 are split as at 26 and 27, that is, their meeting edges are not connected. Consequently these parts can be readily sprung into place.

From the foregoing it will be readily seen that the wheel parts can be easily and quickly assembled and held tightly in place without the use of screws or bolts.

Having thus described my invention, what I claim is:

1. A wheel comprising a hub having circumferential grooves therein, bearing cups and ball bearings therefor mounted on the hub, split wire coils in said grooves to prevent displacement of said ball bearings, a tread member having a side wall resting upon one of said cups, a disk resting upon the other of said cups and engaging the tread member, inner and outer spaced split bands extending between said side wall and said disk, said inner band spanning and resting upon the said cups, and the said outer band snugly seated within the tread member.

2. A wheel comprising a hub, ball bearings and bearing cups therefor on said hub, means for preventing displacement of said balls and bearing cups from said hub, said cups formed with flanges, a tread member

having a side wall at one side and a flange at the opposite side thereof, said side wall adapted to snugly seat against the flange of one of said cups, a disc adapted to snugly seat against the flange on said tread member and against the flange of the other of said cups, and inner and outer split ring like bands clamping said disc against said

last two mentioned flanges, and holding said cups apart and against the bearings. 10

In testimony whereof I affix my signature in presence of two witnesses.

HERMAN CASLER.
